DESIGN FOR A HOUSING FOR THERMO- STATIC CONTROL

Carl G. Bjornerantz, Evanston, and Jon W. Hauser, Oak Park, Ill., assignors to Sears, Roebuck and Co., Chicago, Ill., a corporation of New York

Application May 2, 1946, Serial No. 129,508

Term of patent 14 years

(Cl. D52—7)

To all whom it may concern:

Be it known that we, Carl G. Bjorncrantz and Jon W. Hauser, citizens of the United States and residents, respectively, of Evanston and Oak Park, in the county of Cook and State of Illinois, have invented a new, original, and ornamental Design for a Housing for Thermostatic Control, of which the following is a specification, reference being had to the accompanying drawing, forming a part thereof.

Fig. 1 is a front elevational view of a housing for thermostatic control embodying our new design.

Fig. 2 is a top plan view thereof.

Fig. 3 is an elevational view of the same taken from the right side of Fig. 1.

We claim:

The ornamental design for a housing for thermostatic control, substantially as shown.

CARL G. BJORNCRANTZ.
JON W. HAUSER.
